United States Patent Office.

GEORGE W. SCHERMERHORN, OF EAST LIMINGTON, MAINE.

Letters Patent No. 82,355, dated September 22, 1868.

IMPROVED CORK-PULLER.

The Schedule referred to in these Letters Patent and making part of the same.

TO ALL WHOM IT MAY CONCERN:

Be it known that I, GEORGE W. SCHERMERHORN, of East Limington, in the county of York, and State of Maine, have invented a new and improved Instrument for Removing Corks from Bottles; and I do hereby declare that the following is a full, clear, and exact description thereof, which will enable others skilled in the art to make and use the same, reference being had to the accompanying drawings, forming part of this specification.

Figures 1, 2, and 3 are views representing my improved instrument in different positions in removing the corks from the bottles.

Similar letters of reference indicate corresponding parts.

My invention has for its object to furnish a neat, simple, cheap, effective, and convenient instrument for removing corks from bottles; and it consists in the instrument constructed and arranged, as hereinafter more fully described.

A is the handle of the instrument, which I generally prefer to make about three inches long. Upon one end of the handle A is formed a cylindrical stem, B, about five inches long, and of such a size as to pass freely into the necks of the bottles from which the corks are to be removed. C is a cork disk, fitting upon the stem B, so as to slide back and forth upon it, and of such a size as to fit upon and cover the mouth of the said bottles. D is a loop, made of watch-spring steel, or other suitable elastic and flexible material, the ends of which are secured to the handle A. E is the cork disk, similar to the disk C, and through which the parts of the loop D are passed, as shown in the drawings.

In using the instrument, the end of the stem B is placed upon the outer end of the cork to be removed, the disk or slide C is pushed down so as to rest upon the mouth of the bottle, and pressure is applied to the end of the handle A, until the cork is pushed into the bottle, as shown in fig. 1. The instrument is then removed, and the loop D is inserted into the bottle to grasp the cork, as shown in fig. 2. The disk or slide E is then pushed down upon the mouth of the bottle, and held while the cork is being drawn up into the neck of the bottle, until its upper end is drawn against the said disk E, after which it is easily drawn out, the disks C and E preventing the contents of the bottle from being spilled or spattering out during the operation.

I claim as new, and desire to secure by Letters Patent—

The instrument for removing corks from bottles, consisting of the handle A, having the stem B and spring-loop D at right angles to each other, and provided respectively with the sliding disks C and E, all constructed and arranged to operate as described, whereby the cork is first pushed into the bottle by the stem B, and afterwards withdrawn by the loop D, the disks C E in both operations serving to prevent the contents of the bottle from spattering out, as herein shown and described.

GEORGE W. SCHERMERHORN.
